Primary Examiner — Jeffrey D Asch(74) *Attorney, Agent, or Firm* — Banner & Witcoff, Ltd.(57) **CLAIM**

The ornamental design for a handset, as shown and described.

DESCRIPTION

FIG. 1 is a perspective front view of a handset showing our new design;

FIG. 2 is a perspective rear view thereof;

FIG. 3 is a front view thereof;

FIG. 4 is a rear view thereof;

FIG. 5 is a left side view thereof;

FIG. 6 is a right side view thereof;

FIG. 7 is top view thereof;

FIG. 8 is a bottom view thereof;

FIG. 9 is a perspective front view of a second embodiment of the handset of FIGS. 1-8 showing our new design;

FIG. 10 is a perspective rear view thereof;

FIG. 11 is a front view thereof;

FIG. 12 is a rear view thereof;

FIG. 13 is a left side view thereof;

FIG. 14 is a right side view thereof;

FIG. 15 is top view thereof; and,

FIG. 16 is a bottom view thereof.

The broken lines shown throughout the views that are immediately adjacent to the shaded areas, and define unshaded regions, represent the bounds of the embodiment in which they are shown, while all other broken lines are directed to environment and are for illustrative purposes only; the broken lines form no part of the embodiment in which they are shown.
